AERIAL SYSTEM

Peter Hans Karl Gabriel Cornelius, Eindhoven, Netherlands, assignor to Hartford National Bank and Trust Company, Hartford, Conn., as trustee

Application May 5, 1947, Serial No. 746,075;
In the Netherlands May 21, 1946

6 Claims. (Cl. 250—33)

1

The invention relates to aerial systems for transmitting short waves, which comprise at least two radiators arranged side by side and parallel to one another, the mutual distance between these radiators being small with respect to the length of a radiator. Preferably, a short-circuit is provided between the corresponding ends of the radiators; it is frequently advantageous that each of these short-circuits extends—viewed in the direction of the length of the radiators—over a portion of the radiator length, for example over a portion larger than $1/20$ and smaller than $1/5$ of the radiator length.

In known constructions of the above-mentioned aerial system, the radiators are formed by a plurality of tubes connected to one another by means of cross-pieces. Such a construction is heavy, has an unaesthetic appearance, moreover, catches much wind, can be arranged only with comparatively great difficulty and is therefore less suitable for use in airplanes.

The invention has for its object to provide a simple, cheap and handy construction of the known aerial system which does not exhibit the above-mentioned disadvantages.

According to the invention, the aerial system is constituted by a member which has the shape of a single elongated rod, plate or tube and in which one or more slits are provided which extend in the longitudinal direction.

The said member preferably consists of a single rod, tube or plate in which one or more slits are provided, so that, when starting from rods or tubes of standardized dimensions, it is possible to manufacture aerial systems whose adaptation resistance may have in practice any possible value if only the slits are provided at a suitable point.

The aerial system may also be built-up of two tubes of U-shaped cross-section whose open sides are turned towards one another, or again of a tube of U-shaped cross-section and a plate located in front of the open side of this tube, the spacing between the two tubes or between the tube and the plate being small with respect to the tube length.

Also in this way it is possible, when starting from standardized profiles, to construct aerial systems having an adaptation resistance which exhibits a plurality of different values.

By providing the slits in such manner that they extend more or less far towards the ends, it is possible to obtain at these ends a short-circuit of the radiator which extends over a shorter or

2

longer portion of the radiator length. Owing to the use of a short-circuit extending over a portion of the radiator length, the aerial system is better suitable for transmitting oscillations of a wide frequency-band.

The invention will be explained more fully with reference to the accompanying drawing which represents, by way of example, some embodiments thereof.

Fig. 1 represents an aerial system as is known under the designation "folded dipole." This system consists of two tubes AB and CD which are connected to one another by means of cross-pieces. These tubes act as radiators and have each a length which approximately corresponds to half the wavelength of the electrical oscillations to be transmitted. In the middle the radiator CD is interrupted in view of the connection of a feeder V. The adaptation resistance of this aerial system when tuned amounts approximately to 250 ohms. As is well-known, this resistance may be decreased or increased by making the fed radiator thicker or thinner respectively than the other radiator.

The above-described construction of the folded dipole is, as set out hereinbefore, comparatively heavy, has an unaesthetic appearance, catches much wind, and cannot be arranged as easily as a single dipole.

Fig. 2 now represents an aerial system according to the invention. This aerial consists of a metal tube exhibiting on either side slits extending in the longitudinal direction of the tube so that two radiators AB and CD are formed which are spaced from one another by a distance which is small relatively to the length of a radiator. One of the radiators thus formed (CD) is interrupted in order to permit of connecting the feeder V.

By providing the slits on a chord (see Fig. 2b) instead of on a diameter (see Fig. 2a), it is possible to alter the adaptation resistance of the aerial system. It is also possible to provide a larger number of slits.

Starting from a solid rod, it is possible to obtain a folded dipole even by providing only one slit.

Figs. 3 and 3a show the construction of a folded dipole constituted by two U-shaped bars U₁ and U₂ the open sides of which are turned towards one another. At the ends A,C and B,D the bars are united, for example by welding.

Figs. 4 and 4a represent a similar construction consisting of a U-shaped bar and a plate ar-

ranged in front of the open side of this bar. The spacing between the U-shaped bars in Fig. 3 and that between the U-shaped bar and the plate in Fig. 4 are small with respect to the length of the bar.

By a suitable choice of the dimensions of the U-bars, more particularly of the ratio between the bar heights $a_1: a_2$, it is possible to obtain a number of different values for the adaptation resistance of the aerial system so that suitable adaptation to feeders having surge impedances of different values can be obtained.

The bars U_1 and U_2 may be obtained, for example, by bending plates.

If desired the above-described aerial systems may, be closed at the ends by means of plates.

The aerial systems according to the invention exhibit the shape of a single dipole, are of light construction, have an aesthetical appearance and exhibit only a slight air resistance.

What I claim is:

1. A high-frequency aerial structure comprising a tubular conductive member having a length corresponding substantially to half a wave-length of the operating frequency and provided with a longitudinal slit passing completely through said member and extending from a point adjacent one end of said member to a point adjacent the other end thereof to define two parallel conductors whose corresponding ends are interconnected, one of said conductors being provided with a transverse slit at the midpoint thereof to define the two separate elements of a dipole.

2. A high-frequency aerial structure comprising an open-ended hollow conductive member having a length corresponding to half a wave-length of the operating frequency and provided with a longitudinal slit passing through the member and extending from a point adjacent one end of said member to a point adjacent the other end thereof to define two parallel conductors whose corresponding ends are interconnected, one of said conductors being provided with a transverse slit at the midpoint thereof to define the two separate elements of a dipole, and feeder terminals on adjacent ends of said two elements.

3. A high-frequency aerial structure comprising a hollow conductive member of circular cross section having a length corresponding substantially to half a wavelength of the operating frequency and provided with a longitudinal slit passing through a diametrical plane in the member and extending from a point adjacent one end of said member to a point adjacent the other end thereof to define two parallel conductors whose corresponding ends are interconnected, one of said conductors being provided with a transverse slit at the midpoint thereof to define the two separate elements of a dipole, and feeder terminals on adjacent ends of said two elements.

4. A high-frequency aerial structure comprising a hollow conductive member of circular cross section having a length corresponding substantially to half a wavelength of the operating frequency and provided with a longitudinal slit passing through a chordal plane in the member and extending from a point adjacent one end of said member to a point adjacent the other end thereof to define two parallel conductors whose corresponding ends are interconnected, one of said conductors being provided with a transverse slit at the midpoint thereof to define the two separate elements of a dipole, and feeder terminals on adjacent ends of said two terminals.

5. A high-frequency aerial structure comprising a hollow conductive member of rectangular cross section having a length corresponding substantially to half a wavelength of the operating frequency and provided with a longitudinal slit passing through opposing walls of the member and extending from a point adjacent one end of said member to a point adjacent the other end thereof, said slit being positioned to define two parallel U-shaped conductors whose corresponding ends are interconnected, one of said U-shaped conductors being provided with a transverse slit at the midpoint thereof to define the two separate elements of a dipole, and feeder terminals on adjacent ends of said two elements.

6. A high-frequency aerial structure comprising a hollow conductive member of rectangular cross section having a length corresponding to half a wavelength of the operating frequency and provided with a longitudinal slit passing through opposing walls of the member and extending from a point adjacent one end of said member to a point adjacent the other end, said slit being positioned to define a U-shaped conductor disposed in parallel relation with a planar conductor, the corresponding ends of the conductors being interconnected, the planar conductor being provided with a transverse slit at the midpoint thereof to define the two separate elements of a dipole, and feeder terminals on adjacent ends of said two elements.
